UNITED STATES PATENT OFFICE.

ERICH GERBEL, OF MANNHEIM, GERMANY.

MACHINE FOR WORKING UP CERAMIC MASSES INTO TILES, DISKS, AND SIMILAR BODIES.

1,420,093.

Specification of Letters Patent. Patented June 20, 1922.

Application filed March 25, 1922. Serial No. 546,796.

To all whom it may concern:

Be it known that I, ERICH GERBEL, of German nationality, residing at Mannheim, Germany, have invented a new and useful 5 Improvement in Machines for Working Up Ceramic Masses into Tiles, Disks, and Similar Bodies, for which I filed an application in Germany October 11, 1920, No. G- 52382 VI/80A, not yet granted, and of which 10 the following is a specification.

This invention relates to improvements in machines for working up ceramic masses into tiles, disks and similar bodies and the object thereof is to enable ceramic masses 15 of a fatty texture and especially ceramic masses containing a high percentage of non-plastic ingredients or of a very lean texture to be built up into large cylinders, blocks and such like bodies, wherein are 20 contained a number of the articles to be made, and these bodies to be trued to finished size and cut into disks, tiles and such like articles in one setting up.

In the accompanying drawings I have illustrated novel machines for carrying out my improved process. In the drawing Figure 1 is a lateral view of the whole machine with supporting column on the left and cutting off device and tile rest on the right.

30 Figure 2 shows the cutting off device and tile-rest by itself, seen from the column and table.

Figure 3 is a view of the tile-rest.

Figure 4 is a section on line 4—4 of Figure 1 through the column and holder.

Figures 5 and 6 show details of the tile-rest.

Similar letters refer to similar parts throughout the several views.

40 The machine consists of the bed *a*, on which the column *c* bolted to foundation plate *b* slides by means of the chain wheels *d* and *d'* rack and pinion; the table *e* vertically adjusted by rack, pinion and hand-wheel, carries the cylindrical ceramic body *f* shown as an example, which is to be cut up into circular disks or slabs.

45 The cylinder is first of all trued up on the periphery to finished size by means of 50 the revolving knife *l* carried on the telescopic spindle *g* which rotates through the bevelled wheels *h*, *h'* and *h''* and step cone pulley *i* of which the lower portion can be raised and lowered by lever *k* in the usual 55 way.

Thereupon the arm carrying spindle *g*, which swivels on column *c*, is swung out of the way through an angle of about 90° and the cutting up of the cylinder into disks begins.

60 Column *c*, carrying the cylindrical body *f* slides on bed *a* towards the two belt driven pulleys *m* carrying a narrow band saw *n* and, by passing the cylinder along between these two pulleys *m* the disks are 65 completely sawn off by the band saw *n*, the vertical position of the cylinder having obviously been fixed to the desired height by means of the above mentioned hand wheel, 70 rack and pinion.

75 In view of the comparatively small cohesion of the lean ceramic objects, of which the bodies consist, the disks must be supported during the cutting off period, as otherwise the overhanging portion of the disk which is being sawn off, will break as soon as the saw *n* has penetrated to a certain depth into the cylinder. The tile-rest or catching device provided for this purpose consists of U shaped tension frame *o* 80 with the open end towards column *c* over which a number of steel bands are tightly drawn in the same plane as the saw.

These steel bands enter whilst cutting-off into the cutting or interspace between disk, 85 which is being severed and the remainder of the block, fill it practically up and being of the same thickness as the saw blade, they support the disk, which is being cut off, during the cutting off period, providing a 90 rest for it. Figure 5 shows two of these steel bands from above and Figure 6 is a section through the tension frame with tension device for the steel bands.

95 The gaps between the two steel bands will take up the shavings generated when cutting.

With masses containing non-plastic material of fine grain with cylinders of a small diameter, a perforated sheet across the tension frame or a similar rest of corresponding thickness can be used instead of the steel bands.

100 The V shaped holder *q* fixed to column *c* adjustable horizontally by means of two 105 toothed shafts and slotted, as at *q'*, in the height of the saw blade, details of which are given in Figure 4, showing section 4—4 is pushed up during cutting off period against the cylinders prevents the tilting 110

of same, the breaking off of the outside edge of the disk and the cylinder, as the saw blade breaks through, and serves at the same time to push the disk, which has been cut off, with ease on the steel-band rest.

The slot provided in the holder allows the saw to advance far enough.

This holder can also have the shape of a quadrant or any other shape corresponding 10 to that of the block or cylinder.

After a disk has been cut off, the column *c* and with it the cylinder *f* return to the original position, where if necessary the upper portion of the periphery is trued up 15 by the afore described revolving knife *l*.

The table *e* is thereupon raised by means of the rack, pinion and handwheel or any other mechanical device to the height corresponding to the thickness of the next disk 20 to be cut off and the process of cutting off is repeated, the disk previously sawn off, which is now ready for burning, having been removed from the support.

Where disks provided with centre holes 25 are wanted, as for instance is the case of grinding wheels, a corresponding drill is inserted into the hollow sleeve at the bottom end of the spindle *g* and the wheel is bored simultaneously and the periphery of 30 the cylinder turned by means of the revolving knife *l*.

This knife should not be too long and only a portion of the cylinder should be turned up at one time and after cutting off that 35 portion, the cylinder should return to the position centrally beneath spindle *g* and a further portion should be trued up.

The machine will serve also for cutting 40 off square, rectangular or any other irregular shapes, whereby the sides are worked up on the machine over templets, the holder *g* altered accordingly and the revolving knife *l* not used.

Where large disks or slabs are to be made, 45 it will be advantageous to provide a revolving table instead of a stationary one and to rotate the blocks or cylinders, truing the periphery with a stationary tool.

The principle of the invention can also be 50 carried out in such a way that the cylinders are laid horizontally on a support of the corresponding shape and slotted according to thickness of the disk wanted or by bedding the cylinders or blocks on some plastic support, which can easily be cut and cutting 55 these blocks by means of a vertical band saw

of well-known construction into disks, slabs or tiles.

The process may be also utilized for cutting up masses containing a small percentage of non-plastic material, especially where these have been made by the casting or slush process.

I claim:

1. In a machine for making disk-shaped 65 objects and the like from ceramic masses, a vertically adjustable support for a mass block; means for truing the mass; means for successively cutting disks from the mass, and means for receiving and supporting the 70 cut disks, the said adjustable support and the said disk cutting means being arranged for relative movement toward and from each other.

2. In a machine for making disk shaped 75 and similar objects from ceramic masses, a mass supporting table; a swing arm carried by the machine; a rotating rising and falling spindle on said swing arm, a rotating knife carried thereby and arranged to true 80 the mass, and a saw for successively cutting disks from the mass, said table being mounted for movement toward and from said saw.

3. In a machine for making disk-shaped 85 objects and the like from ceramic masses, a vertically adjustable support for a mass block; means for truing the mass; means for successively cutting disks from the mass, and means for receiving and supporting the 90 cut disks, the said adjustable support and the said disk cutting means being arranged for relative movement toward and from each other, and the said mass truing means being arranged for movement to and from the mass block.

4. In a machine for making disk shaped 95 and similar objects from ceramic masses, a mass block supporting table; a cutting member in the machine a U shaped tension frame provided in conjunction with the cutting member; and steel bands drawn over the said frame and separated from each other by small interspaces, said bands being of the same thickness as the cutting member and adapted to support the objects as they are 100 cut off.

Signed at Manchester, England, this 3rd day of March, 1922.

ERICH GERBEL.
